METHOD OF ATTACHING PLUG RECEIVING
MEMBERS TO METAL CONTAINERSDavid W. Curtis, Richmond, Calif., assignor, by
direct and mesne assignments, of fifty per cent
to Thomas Connors, St. Louis, Mo.

Application October 5, 1934, Serial No. 747,024

5 Claims. (Cl. 29—148.2)

This invention pertains to metal barrels and similar containers, and more particularly is a method by which such container may be provided with a suitable opening for any desired purpose, particularly where it is desirable that such an opening be closed by a screw plug or similar closure element.

It is well known that the walls of metal drums, barrels and similar containers are usually entirely too thin to permit of screw threading to a sufficient degree to receive and retain a removable closure plug. I have overcome this difficulty by providing a process whereby such a container may be provided with an opening possessing the thickness of metal sufficient to provide ample screw thread anchorage for a removable plug, and it is therefore the object of this invention to provide a process by means of which the above result may be effectively and economically accomplished.

The invention will be hereinafter fully set forth and particularly pointed out in the claims.

In the accompanying drawings, Fig. 1 is a cross sectional view illustrating a plug-receiving member constructed and arranged to be secured to a drum barrel or the like. Fig. 2 is a similar view showing the plug-receiving member initially engaged with a flange formed around an opening in a container of the type mentioned. Fig. 3 is a similar view to Fig. 2 illustrating another stage of the process of uniting the plug-receiving member to the wall of the container. Fig. 4 is a similar view illustrating the plug-receiving member in its final position. Fig. 5 is a side elevation illustrating the method of crimping the exterior of the plug-receiving member to prevent rotation thereof with respect to the wall of the container. Fig. 6 is a vertical sectional view on the line 6—6 of Fig. 4.

Referring to the drawings, P designates a plug-receiving member constructed of metal and provided with a central screw threaded opening 10. Said member is also provided with an annular groove 11 having an inner flange 12 and an outer flange 13 on the opposite sides thereof. It will be noted that in Fig. 1 the flange 13 is shown in a slightly divergent position and is provided with an enlargement 14 at its edge. The drum barrel or other container is indicated at B, the same being provided with an opening 15 formed by pressing the metal outward so as to form an annular flange 16, with inturned edges 17.

In practice, a blank such as indicated in Fig. 1, is engaged with the flange 16, by causing the

flanges 12 and 13 to straddle said flange 16, a suitable packing C having first been placed upon the inturned edge 17 of the flange 16. The parts are then held in suitable manner and the flange 12 is bent outwardly, as indicated at 18 of Fig. 2, so as to overlap the inturned edge 17. The flange 16 is then pressed inwardly as indicated in Fig. 3, the pressure being sufficient to slightly offset the metal, as indicated at 19, and to crimp the flange 16 inwardly, as indicated at 16a of Fig. 3. At this stage the parts are definitely interlocked, whereupon further pressure is applied in a direction tending to squeeze the packing C, in such manner as to spread it over the bottom of the groove 11, and to also squeeze the bent portions 17 and 18 and the flanges 13 and 16 more closely together, as indicated in Fig. 4. After this operation, the parts are so secured together that they become practically an integral unit. Out of an abundance of caution, to prevent relative rotation of the part P with respect to the part B, a radial crimping pressure is applied so as to provide the inwardly crimped portions 20 in the flange 13, which are of sufficient magnitude to slightly offset the flange 16, as clearly shown in Fig. 6, thereby providing a definite interlock between the plug-receiving member and the container.

The advantages of the invention will be readily appreciated by those skilled in the art to which it belongs. For instance, it will be particularly noted that the member P may be made of sufficient thickness to provide ample surface for a screw thread, and therefore provides a simple and efficient means of equipping a metal container with a removable screw plug closure. It will also be observed that the parts are so intimately connected with each other that they constitute to all intents and purposes an integral structure and will not become loosened or separated.

Having thus explained the nature of the invention and described an operative manner of constructing and using the same, although without attempting to set forth all of the forms in which it may be made, or all of the forms of its use, what is claimed is:

1. The method of attaching a plug-receiving member to a metal container, comprising providing the container with a hole having a flange surrounding the same, said flange having an inwardly bent edge, providing a plug-receiving member having parallel concentrically spaced inner and outer flanges, engaging said member with the flange of the container in such manner that the flanges of the plug-receiving member straddle the flange of the container, bending the inner

flange of said member in a manner to overlap the inturned edge of the container flange and then squeezing all of said flanges together.

2. The method of attaching a plug-receiving member to a container, comprising forming a hole in the container and forming a flange around said hole, providing a plug-receiving member having concentrically spaced inner and outer annular flanges, engaging said member with the container flange in such manner that the latter is interposed between the flanges of said member, interposing a packing washer between the container flange and said member, bending the container flange and the inner flange of the plug-receiving member into parallel relationship, bending the outer flange of the container member into engagement with said container flange, then compressing all of said flanges into engagement by movement of the plug-receiving member toward the body of the container, and then crimping portions of said outer flange radially inward to a sufficient extent to correspondingly offset portions of the container flange so as to hold the parts against relative rotation.
3. The method of attaching a plug-receiving member to a metal container, comprising providing the container with a hole having a flange surrounding the same, said flange having an inwardly bent edge, providing a plug-receiving member having concentrically spaced inner and outer flanges, engaging said member with the flange of the container in such manner that the flanges of the plug-receiving member straddle the flange of the container, bending the inner flange of said member in a manner to overlap the inturned edge of the container flange and then squeezing all of said flanges together, and pressing radially inwardly spaced portions of the outer flange to such an extent as to interlock with and slightly offset adjacent abutting portions of the container flange.

4. The method of attaching a plug-receiving member to a metal container which comprises,

providing the wall of the container with an embossed portion having an aperture therein provided with a peripheral flange, providing a substantially cylindrical plug-receiving member having a cylindrical inner flange and a cylindrical outer flange spaced from said inner flange to provide an annular space therebetween, said inner flange lying substantially parallel with the axis of the member and said outer flange diverging substantially with respect to said axis, engaging said member with the embossed portion of the container so that the aperture flange thereof is positioned in said annular space, and securing said flange in said space by bending said inner flange to a position wherein it lies substantially transverse with the axis of said member, and bending said outer flange so that it lies parallel with said axis.

5. The method of attaching a plug-receiving member to a metal container which comprises, 20 providing the wall of the container with an embossed portion having an aperture therein provided with a peripheral flange, providing a substantially cylindrical plug-receiving member having a cylindrical inner flange and a cylindrical outer flange spaced from said inner flange lying substantially parallel with the axis of the member and said outer flange diverging substantially with respect to said axis, engaging said member with the embossed portion of the container so that the aperture flange thereof is positioned in said annular space, and securing said flange in said space by bending said inner flange to a position wherein it lies substantially transverse with the axis of said member, and overlying said aperture flange, bending said outer flange so that it lies parallel with said axis and adjacent said embossed portion of said container, and displacing from the main body of said outer flange alternate peripheral portions thereof and adjacent corresponding portions of the embossed portion of said container. 30 35 40
